US00D877135S

(12) **United States Design Patent** (10) **Patent No.:** **US D877,135 S**
Kim (45) **Date of Patent:** **** Mar. 3, 2020**

(54) **CASE FOR ELECTRONIC COMMUNICATIONS DEVICE**

(71) Applicant: **SPIGEN KOREA CO., LTD.**, Seoul (KR)

(72) Inventor: **Ji Hyun Kim**, Seoul (KR)

(73) Assignee: **SPIGEN KOREA CO., LTD.**, Seoul (KR)

(**) Term: **15 Years**

(21) Appl. No.: **29/676,438**

(22) Filed: **Jan. 10, 2019**

(51) **LOC (12) Cl.** **14-03**

(52) **U.S. Cl.**

USPC **D14/250**

(58) **Field of Classification Search**

USPC ..... D3/201, 218, 226, 227, 247, 249, 250, D3/269, 303; D13/103, 107, 108, 119; D14/137, 138 R, 138 AA, 138 C, 138 G, D14/172, 192, 203.3–203.7, 217, 238.1, D14/247, 248, 250–253, 440, 447

(57) **CLAIM**

The ornamental design for a case for electronic communications device, as shown and described.

DESCRIPTION

FIG. 1 is a front perspective view of a case for electronic communications device, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines throughout the drawing figures depict portions of the case for electronic communications device that form no part of the claimed design.

1 Claim, 8 Drawing Sheets
